UNITED STATES PATENT OFFICE.

ART J. SHIRK AND SOLOMON COHEN, OF NEW YORK, N. Y., ASSIGNEES TO ABRAHAM S. ISERSON, OF NEW YORK, N. Y.

ELECTRIC PRESS IRON.

1,421,587.

Specification of Letters Patent.

Patented July 4, 1922.

Application filed March 6, 1920. Serial No. 363,913.

To all whom it may concern:

Be it known that ART J. SHIRK and SOLOMON COHEN, citizens of the United States, and residents of the city of New York, in the county of New York and State of New York, have invented certain new and useful Electric Press Irons, of which the following is a specification.

This invention relates to electric press irons and is directed to an automatic switch and stand therefor adapted to facilitate the use of such irons, increase the efficiency thereof and effect economy of power and material and longer life of the iron and its parts and attachments.

More particularly the invention relates to a stand and automatic switch for electric irons whereby the circuit is closed and the iron heated when the same is in place on the stand and the circuit broken when the iron is removed from the stand by the operator.

One object of our invention is to provide in an iron and stand of the character described an automatic switch of simple construction and positive, quick and efficient in its operation.

Another object of our invention is to provide a stand and automatic switch for electric press irons for the purpose described and which shall be adapted for use with any stand electric heating irons without necessitating more than very simple and easily made modifications or attachments thereto and which shall be further simple, positive and efficient in operation and cheap and easy to manufacture.

A further object of our invention is to provide an automatic switch for electric press irons and the like apparatus adapted to be operated by the weight of the iron to connect the electric supply thereto.

A still further object of our invention is to provide an automatic switch of the character described which may be adjusted for operation with various weights of irons.

Other objects and advantages of this invention will appear from the detailed description and the features of novelty will be particularly pointed out in the claims.

In the drawing accompanying this specification and forming a material part thereof,

Fig. 1 is a vertical cross-sectional view of our improved stand and automatic switch

with the parts shown in "off" position; that is with the heating iron or other such apparatus not in place on the stand;

Fig. 2 is a similar cross-sectional view of our improved stand and automatic switch with the parts in "on" position, that is with the iron on the stand and the circuit made through the iron;

Fig. 3 is a detailed cross-section in plan cut along line 3—3 of Fig. 2;

Fig. 4 is a partial cross-sectional view cut along line 4—4 of Fig. 2;

Fig. 5 is a partial cross-sectional view in elevation of a modification showing a simplified form for the switch mechanism and also showing an adaptation of our invention for making a touch contact with the iron instead of socket contact; and

Fig. 6 is a partial detailed cross-sectional view in plan cut along line 6—6 of Fig. 5.

Referring in detail to the drawing, the heating stand comprises a base portion 10 and the support 11 for the iron or like electrical apparatus 12. Extending from the rear of the stand is a casing 13 lined on the inside with insulating material such as 14, 14'. The casing is closed at the top and the rear side by insulating material such as the composition material 15, 15'. Within this casing is mounted the automatic switch mechanism which will not be described.

A pair of actuating arms 16, 16' are pivoted to the sides of the casing as at 17, 17' and are provided at the free ends with a projection or ear 18, 18'. The free ends and projections of the arms 16, 16' and the ears 18, 18' are adapted to normally project above the bottom of the support 11 as through an opening therein as shown in Fig. 1 when the iron is not in position on the stand. Pivoted to each of the arms 16, 16' as at 19, 19' is a link member 20, 20' and pivoted to each of the latter as at 21, 21' is an insulated arm 22, 22' and a contact arm 23, 23' having one end thereof shaped as at 23^a so as to form a plug adapted to enter into the contact sockets 24, 24' which connect with the heating coil of the iron or other electric apparatus (not shown).

The other ends of these contact arms are bent away as at 23^b so as to be disposed in operative relation to the contact clips 29 hereinafter referred to. The arms 22, 22'

are further pivoted on a shaft 25 journaled in bearing member 26 suitably secured to the side of the casing as at 27. Secured within the casing as at the top, by means of screws or the like fastening means 28 are the contact clips 29, 29' in operative relation to the bent ends 23^b of the contact arms. The contact clips 29, 29' are connected to the electric supply by means such as binding posts and lead wires 30 as will be readily understood.

The operation of our heating stand and automatic switch will now be understood. The actuating arms 16, 16' are normally in the inclined position shown in Fig. 1 with the free ends thereof projecting above the support 11 by reason of the overweight of the parts of the switch mechanism to the right of the fulcrums 17 and 17' respectively, as will be readily understood. When the iron or the like apparatus is placed in position on the stand as in Fig. 2, the weight of the iron acting downward on the ears 18, 18' of the arms 16, 16' force the arms to move forward about the pivots 20, 20' until they reach a substantially horizontal position as shown in this figure. The links 19, 19' move upward and become substantially vertical, at the same time causing the link members 22, 22' and the contact arms 23, 23' to rotate about their pivot 21 into substantially horizontal position when the ends 23^a enter the sockets 24 on the rear of the iron and the ends 23^b make contact with the clips 29, 29' as shown in Figs. 2, 3 and 4, thus connecting the heating coil to the electric supply through said contact arms 23, 23' as will be readily understood.

In the modified form illustrated in Figs. 5 and 6, we have shown a simplified construction operating on the same principle in which, however, the contact arms 23^c, 23^d (having the same function as members 23, 23' hereinabove described) are pivoted on one shaft preferably of insulating material adapted to be operated by a single arm 16^a similar in construction and functioning in the same manner as the arms 16, 16' hereinabove referred to. Pivoted to this arm 16^a is a single link member 20 which is pivoted at its upper end centrally on the shaft 31 as at 33. In this modified form the contact arms 23^c, 23^d are provided with elongated slots 34 at the forward contacting ends thereof adapted to slide over the pins 35, 35' suitably secured in the sides of the casing. Instead of a socket contact we have in this modified form shown a touch contact, the ends of the arms 23^c, 23^d being bent to provide contacting pieces 36, 36' adapted to make touch contact with the contact studs 37, 37' on the rear of the iron. To maintain the switch mechanism in position when the iron is on the stand as shown in full lines in Fig. 5, we provide a spring member

38 suitably secured within the casing as at 39 position so as to abut against the link 20 and press thereagainst.

Inasmuch as standard electric heating irons as now manufactured are of several standard weights, and adjustable counterpoise 40 may be mounted on the free end of the arms 16^a and adapted to be moved along said arm so as to adapt it for being operated by a corresponding weight of iron placed on the stand.

The operation of our modified form is similar to that of the form shown in Figs. 1, 2, 3 and 4. The counter-poise is first adjusted to correspond to the weight of the iron to be used. As the iron is placed on the stand it pushes downward on the arm 16 which in turn pushes upward on the link 20, thus causing the contact members 23^c, 23^d to rotate about the shaft 31 from the dotted position shown in Fig. 5 into the position shown in full lines, the slots 34 moving over the pins 35, 35' until they lodge in the ends of the slot. The rear ends 23^c of the contact arms 23^c, 23^d snap into the clip 29, 29' while the contact pieces 36, 36' move into touch contact with the studs 37, 37' thus conducting the current from the clips to the irons.

While we have explained and described our invention in connection with the use thereof with electric irons, it will, of course, be understood that my improved heating stand and switch mechanism may be used with any electric tool or apparatus having suitable contacts and designed to be electrically heated or otherwise connected to a source of electric supply.

Having thus described my invention, I claim as new and desire to secure by Letters Patent:—

1. In an electric heating stand for sad irons and the like, a support for the iron, an actuating member extending normally above the surface of said support, said actuating member adapted to be adjusted to be operated by different weights of iron when placed in position on the support, a contact making arm, means for transmitting motion from said actuating member to said contact making arm whereby the latter connects the electric circuit to the iron, and means for normally maintaining said actuating arm above the support in position to be operated by the iron.

2. In an electric heating stand for electric sad irons and the like, an automatic switch for connecting the iron to the electric supply comprising a contact clip connected to the electric supply, an actuating lever, a link member pivoted thereto and a contacting lever pivoted to said link member, adapted to be operated by the actuating lever to make contact with said contact clip.

3. The combination with an electric sad iron or the like apparatus having contacts thereon, of an automatic switch for connecting said iron to the electric circuit, comprising a contact clip connected to the electric supply, an actuating lever, a link member pivoted thereto, and a contacting lever pivoted to said link adapted to be operated by the actuating arm to make contact with said contact clip and with the contacts on 10 said iron.

Signed at New York city, in the county of New York and State of New York, this 5th day of March A. D. 1919.

ART J. SHIRK.
SOLOMON COHEN.
